NUT

Phillip G. Holliday, Bellwood, Ill., assignor to Standard Screw Company, Bellwood, Ill., a corporation of New Jersey

Filed June 20, 1966, Ser. No. 2,727

Term of patent 14 years

(Cl. D54—9)

FIGURE 2 is a longitudinal section taken at line 2—2
of the top of the nut.

I claim:

The ornamental design for a nut, as shown.
